UNITED STATES PATENT OFFICE.

WALTER R. SCHLAGE, OF SAN FRANCISCO, CALIFORNIA, ASSIGNOR TO SCHLAGE LOCK COMPANY, OF SAN FRANCISCO, CALIFORNIA, A CORPORATION OF CALIFORNIA.

DOOR FASTENER.

Application filed August 2, 1923. Serial No. 655,218.

This invention relates to door fasteners and especially to improvements on the structure shown in my former Patent entitled "Door lock," No. 1,456,041, issued May 22,

5 1923.

The object of the present invention is to provide a fastener which is particularly adapted for installation on French doors and the like; to generally improve and simplify the construction and operation of locks of the character described; to provide a fastener which requires a minimum of cutting, fitting and removal of wood when installed, and which will fit practically any standard 10 door even though the thickness of the same may vary considerably; to provide a fastener which is secured from one side of the door only by an intermediate plate and screws which engage the fastener housing, 15 and further to provide means whereby the securing screws and intermediate plate are entirely concealed when the fastener is in place. Other objects will hereinafter appear.

20 25 One form which my invention may assume is exemplified in the following description and illustrated in the accompanying drawings, in which—

Fig. 1 is a horizontal section of the 30 fastener showing it in position in the door.

Fig. 2 is a section on line 2—2, Fig. 1.

Referring to the drawings in detail, A indicates a fastener housing of unit construction. This housing is cylindrical in 35 cross section and elongated as shown. One end of the housing is closed by an integral end plate 2, and the opposite end by an escutcheon plate 3. The end plate 2 is extended to form a bearing 4, and the escutcheon plate 3 is similarly extended to form a bearing 5. Extending through the bearings 4 and 5 is a knob supporting spindle which is divided into two sections as indicated 40 at 6 and 7; these spindles forming supports for knobs 8 and 9 as shown. The ends of 45 the spindles are square to receive the knobs and to secure the same against turning movement with relation to the spindle sections, and they may be secured by screws or 50 the like as indicated at 10. Formed on the inner end of each spindle section is a circular plate 11 and connecting said plates and the spindle sections 6 and 7 are a plurality of cross-bars as indicated at 12, 13 and 14.

55 The plates 11, together with the connecting

bars 12, 13 and 14, will hereinafter be referred to as the spindle barrel, the barrel being provided for the purpose of retracting a latch 15.

The open end of the cylindrical fastener 60 housing is provided with an annular flange 16. This flange is circular in formation and is beveled to permit the escutcheon plate 3 to be snapped on and secured when the fastener is in position in the door. One 65 side of the fastener housing is cut away as indicated at 17 and an opening is thus formed for the reception of the latch housing generally indicated at 18, the latch housing being secured to the fastener housing 70 in any suitable manner or as here indicated by means of rivets 19. One side of the flange 16 is extended to form a cover plate 20 for the latch housing and a rectangular chamber is thus formed which serves as a 75 guide for the latch 15 and the mechanism whereby it is actuated. This mechanism consists of a pair of inwardly extending arms 21 and 22. These arms are bent at their inner end to form hook like projections 80 23 and they are so positioned as to be engaged by the cross-bars 13 and 14. The latch is normally held in a projected position by means of a helical spring 24, this spring being positioned between the arms 85 21 and 22 and being interposed between the latch 15 and a cross-bar 25.

When it is desired to retract the latch 15 it is only necessary to turn the spindle barrel by means of either knob. This turning 90 movement causes either the cross-bar 13 or the cross-bar 14 to engage the hook like projections 23. Inward movement is thus imparted to the arms 21 and 22 and to the latch 15, and when the knob is released normal position is again assumed as spring 24 is placed under tension when the knobs and spindle barrel are manually turned and thus exert sufficient pressure to return the same 95 to normal position when the knobs are released.

The fastener proper when applied to a door is installed in the following manner: A hole is first drilled through the door with an auger or suitable tool, the hole being of 100 a diameter which will permit the cylindrical casing A to fit snugly therein. The inner face of the door is then channeled to receive the latch housing and the entire operation of cutting the door to install the fas- 110

tener is thus completed. The fastener is next applied by inserting the cylindrical housing and forcing it inwardly until the flange 16 engages the face of the door. The 5 escutcheon plate may then be applied, and an intermediate plate, such as shown at 27, is next applied, this plate being slidably mounted on the bearing extension 4 of the fastener housing. A pair of screws 28 is 10 then passed through the intermediate plate and as the inner ends of the screws have a threaded engagement with the fastener housing at the points indicated at 29, it is obvious that the plate 27 will be pulled taut against 15 the opposite face of the door, while the flange 16 and the escutcheon plate 3 will be pulled snugly against the opposite face of the door. The fastener is in this manner secured to the door and the escutcheon plate 30 is then 20 applied and snapped over the intermediate plate 27. The knob 8 is placed in position and secured by the screw 10 and the whole operation of installing the fastener is completed. No screws are required on the end 25 which is covered by the escutcheon plate 3, and as the screws 28 are hidden by the escutcheon plate 30, it can be seen that the entire fastening mechanism is concealed and the appearance of the fastener is accord- 30 ingly simplified and improved. The fastener is at the same time rigidly secured and can- 35 not be tampered with as the escutcheon plate 30, the intermediate plate 7, and the screws 28, are preferably positioned on the inside of the door.

By referring to Fig. 1, it will be noted that the fastener housing A is slightly shorter than the thickness of the door. This is an important feature as it permits the 40 fastener to be fitted to doors of various thicknesses; that is, the length of the fastener housing A is such that it will take care of a door of minimum thickness, but as the bearing extension 4 extends a con- 45 siderable distance and as the plates 27 and 30 are slidably mounted thereon, doors having a greater thickness can readily be taken care of.

While certain features of the present in- 50 vention are more or less specifically illus- trated, I wish it understood that various changes in form and proportion may be resorted to within the scope of the appended claims; similarly, that the materials and 55 finish of the several parts employed may be such as the experience and judgment of the manufacturer may dictate or various uses may demand.

Having thus described my invention, what 60 I claim and desire to secure by Letters Patent is—

1. A fastener adapted for use in a door having a transverse opening formed therein, comprising a fastener housing insertible in 65 the opening and adapted to be supported

therein, a bearing hub on each end of the fastener housing, a spindle journalled therein and supported thereby, a stop member on one end of the housing engageable with one face of the door and limiting inward move- 70 ment of the fastener housing, a plate engag- ing the opposite face of the door and sup- ported independently of the bearing hubs and spindle, and fastening means connecting said plate and the fastener housing and se- 75 curing said housing against endwise move- ment in the opening.

2. A fastener adapted for use in a door having a transverse opening formed therein, comprising a fastener housing insertible in 80 the opening and adapted to be supported therein, a bearing hub on each end of the fastener housing, a spindle journalled therein and supported thereby, a stop member on one end of the housing engageable with one face of the door and limiting inward move- 85 ment of the fastener housing, a plate engag- ing the opposite face of the door, and fastening means connecting said plate and the fastener housing and securing said hous- 90 ing against endwise movement in the open- ing, said plate and fastening means being adjustable with relation to the housing, the bearing hubs and spindle to take care of doors of various thicknesses. 95

3. A fastener adapted for use in a door having a transverse opening formed therein, comprising a fastener housing insertible in 100 the opening and adapted to be supported therein, a stop member on one end of the housing engageable with one face of the door and limiting inward movement of the fastener housing, a plate engaging the oppo- 105 site face of the door, said plate having a central opening formed therein, bearing hubs on the fastener housing, one of which projects through the plate opening, a spindle journalled in the bearing hubs and also pro- 110 jecting through said opening, said spindle and hubs being supported independently of the plate, and adjustable fastening means connecting said plate and the fastener hous- 115 ing to secure said housing against endwise movement in the opening and to permit longitudinal movement of the housing, bearing hubs and spindle with relation to the plate while applying the fastening means.

4. A fastener adapted for use in a door having a transverse opening formed therein, comprising a fastener housing insertible in 120 the opening and adapted to be supported therein, a stop member on one end of the housing engageable with one face of the door and limiting inward movement of the fastener housing, a plate engaging the oppo- 125 site face of the door, fastening means connect- 130 ing said plate and the fastener housing and securing said housing against endwise movement in the opening, and an escutcheon plate adapted to be secured to said last 135

named plate and adapted to conceal said plate and the fastening means cooperating therewith.

5. A fastener adapted for use in a door 5 having a transverse opening formed therein, comprising a fastener housing insertible in the opening and adapted to be supported therein, a stop member on one end of the housing engageable with one face of the door 10 and limiting inward movement of the fastener housing, a plate engaging the opposite face of the door, fastening means connecting said plate and the fastener housing and securing said housing against endwise movement in the opening, and an escutcheon plate 15 adapted to be secured to said last named plate and adapted to conceal said plate and the fastening means, said escutcheon plate being adjustable in unison with said plate.

20 6. A fastener adapted for use in a door having a transverse opening formed therein, comprising an elongated cylindrical housing insertible in the opening and adapted to be supported therein, a flange on one end of the 25 housing engageable with one face of the door and limiting inward movement of the housing in the opening, a bearing extension formed on the opposite end of the housing and projecting through the opening in the 30 door, a plate slidably mounted on said bearing extension and engageable with the adjacent face of the door, and screws carried by said plate and having a threaded engagement with the fastener housing to secure the 35 same in the opening.

7. A fastener adapted for use in a door having a transverse opening formed therein, comprising an elongated cylindrical housing insertable in the opening and adapted to be 40 supported therein, a flange on one end of the housing engageable with one face of the door and limiting inward movement of the housing in the opening, a bearing extension formed on the opposite end of the housing 45 and projecting through the opening in the door, a plate slidably mounted on said bearing extension and engageable with the adjacent face of the door, screws carried by said plate and having a threaded engagement 50 with the lock housing to secure the same in the opening, and an escutcheon plate slidably mounted on the bearing extension and adapted to be secured to said plate to conceal the plate and the screws carried thereby.

55 8. A fastener adapted for use in a door having a transverse opening formed therein, comprising an elongated cylindrical housing insertible in the opening and adapted to be 60 supported therein, one end of the housing being open and provided with an annular stop flange engageable with one face of the door to limit inward movement of the housing in the opening, the opposite end of the housing being substantially closed and being 65 provided with a bearing member, said bear-

ing member extending through the opposite end of the opening, an escutcheon plate adapted to be secured to the stop flange, a bearing formed thereon, a spindle projecting through the fastener housing and supported 70 in said bearing at one end and in the bearing of the fastener housing at the opposite end, a latch actuating mechanism carried by the spindle interior of the housing, a latch adapted to be actuated thereby, and means 75 engageable with the substantially closed end of the housing and with the adjacent face of the door to secure the housing against endwise movement in the opening.

9. A fastener adapted for use in a door 80 having a transverse opening formed therein, comprising an elongated cylindrical housing insertible in the opening and adapted to be supported therein, one end of the housing being open and provided with an annular stop flange engageable with one face of the door to limit inward movement of the housing in the opening, the opposite end of the housing being substantially closed and being 85 provided with a bearing member, said bearing member extending through the opposite end of the opening, an escutcheon plate adapted to be secured to the stop flange, a bearing formed thereon, a spindle projecting 90 through the fastener housing and supported in said bearing at one end and in the bearing of the fastener housing at the opposite end, a latch actuating mechanism carried by the spindle interior of the housing, a latch adapted to be actuated thereby, means 95 engageable with the substantially closed end of the housing and with the adjacent face of the door to secure the housing against endwise movement in the opening, and an escutcheon plate 100 slidably mounted on the bearing end of the housing and adapted to conceal said securing means.

10. A fastener adapted for use in a door having a transverse opening formed therein, comprising an elongated cylindrical housing 110 insertible in the opening and adapted to be supported therein, one end of the housing being open and provided with an annular stop flange engageable with one face of the door to limit inward movement of the housing in the opening, the opposite end of the housing being substantially closed and being provided with a bearing member, said bearing member extending through the opposite end of the opening, an escutcheon plate 115 adapted to be secured to the stop flange, a bearing formed thereon, a spindle projecting through the fastener housing and supported in said bearing at one end and in the bearing of the fastener housing at the opposite end, a latch actuating mechanism carried by the spindle interior of the housing, a latch adapted to be actuated thereby, a plate 120 slidably mounted on the bearing end of the housing and engageable with the adjacent 125 housing and engageable with the adjacent 130

- face of the door, screws carried by said plate and having a threaded engagement with the substantially closed end of the fastener housing to secure the fastener housing 5 against removal, and an escutcheon plate slidably mounted on the bearing extension of the housing adapted to be secured to said plate, said escutcheon plate concealing said plate and the screws carried thereby.
- 10 11. A fastener adapted for use in a door having a transverse opening formed therein comprising a cylindrical shaped elongated housing insertable in the transverse opening and adapted to be supported therein, said 15 housing having an integral end section and open at the opposite end, a stop member on the open end of the housing engageable with one face of the door to limit inward movement of the housing in the transverse opening, a clamping plate independent of the housing and engageable with the opposite face of the door, and means for securing the housing with relation to said clamping plate.
- 20 12. A fastener adapted for use in a door having a transverse opening formed therein comprising a cylindrical shaped elongated housing insertable in the transverse opening and adapted to be supported therein, said 25 housing having an integral end section and open at the opposite end, a stop member on the open end of the housing engageable with one face of the door to limit inward movement of the housing in the transverse opening, a clamping plate independent of the housing and engageable with the opposite face of the door, means for securing the housing with relation to said clamping plate, 30 an escutcheon plate covering the open end of the housing, a hub member on said plate, a hub member on the closed end of the housing, said hub member projecting through the clamping plate, and a spindle journaled in said hub members.
- 35 13. A fastener adapted for use in a door having a transverse opening formed therein comprising a cylindrical shaped elongated housing insertable in the transverse opening and adapted to be supported therein, said 40 housing having an integral end section and open at the opposite end, a stop member on the open end of the housing engageable with one face of the door to limit inward movement of the housing in the transverse opening, a clamping plate independent of the 45 housing and engageable with the opposite face of the door, means for securing the housing with relation to said clamping plate, an escutcheon plate covering the open end of the housing, a hub member on said plate, 50 a hub member on the closed end of the housing, said hub member projecting through the clamping plate, a spindle journaled in said hub members, a rollback member adapted to be actuated by the spindle, 55 and a latch actuated by the rollback.
